DESIGN FOR AN AIR DISTRIBUTION OUTLET

Raymond M. Page, Rockford, Ill., assignor to
Barber-Colman Company, Rockford, Ill., a
corporation of Illinois

Application September 8, 1939, Serial No. 87,097

Term of patent 14 years

To all whom it may concern:

Be it known that I, Raymond M. Page, a citizen
of the United States, residing at Rockford, in
the county of Winnebago and State of Illinois,
have invented a new, original, and ornamental
Design for an Air Distribution Outlet, of which
the following is a specification, reference being
had to the accompanying drawing, forming part
thereof.

In the drawing, Figure 1 is a perspective view

of an air distribution outlet embodying my new
design.

Fig. 2 is a side elevation, one-half of which is
shown in diametrical section.

Fig. 3 is a bottom view.

I claim:

The ornamental design for an air distribution
outlet, substantially as shown.
